RAILWAY SIGNALING

Filed Sept. 22, 1928

INVENTOR:
P. P. Stoker,
BY A. Z. Venable
His ATTORNEY

UNITED STATES PATENT OFFICE

PAUL P. STOKER, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING

Application filed September 22, 1928. Serial No. 307,644.

My invention relates to railway signaling, and particularly to signaling of the type wherein the signals are manually controlled from a remote point, which may, for example, 5 be a despatcher's office.

One feature of my invention is the provision, in systems of this character, of novel and improved means for the control of what are known as "calling-on" signals.

10 I will describe one form of signaling system embodying my invention, and will then point out the novel features thereof in claims.

The accompanying drawing is a diagrammatic view showing one form of signaling 15 system embodying my invention.

Referring to the drawing, the reference characters 1 and 1^a designate the track rails of a stretch of railway track M over which traffic moves in both directions. These rails 20 are divided by insulated joints 38 to form a track section A—D, and the section A—D contains a switch S which leads from the main track M to a passing siding C.

Section A—D is provided with a track circuit, comprising a battery 2 connected across the rails at one end of the section, and a track relay T connected across the rails at the other end of the section. The track rails of both the main track M and the passing siding C are 30 included in this track circuit in the usual and well known manner.

Eastbound traffic through the section A—D is governed by a signal S^E, having a main arm 3^M, an auxiliary arm 3^A, and a calling-on arm 3^C. Westbound traffic through the section is governed by a signal S^W, having a main arm 3^M, an auxiliary arm 3^A, and a calling-on arm 3^C. In accordance with usual practice, the main arm 3^M and the calling-on 40 arm 3^C of signal S^W are located adjacent the main track M, and the auxiliary arm 3^A is located adjacent the siding C. When either arm 3^M is in the clear position it indicates that switch S is in its normal position and 45 that high speed traffic over this switch is permissible. When either arm 3^A is in the clear position, it indicates that switch S is in the reverse position and that low speed traffic over this switch is permissible. When 50 either calling-on arm 3^C is in the clear posi-

tion, it indicates that section A—D is occupied but that a closing-in movement is permissible.

The reference character K designates a switch indication relay which is controlled by a pole-changer 4 operatively connected with the switch S. When the switch is in the normal position, relay K is energized in the normal direction, whereas when the switch is in the reverse position this relay is energized in the reverse direction. The circuit for relay K will be obvious from the drawing.

The signals are controlled by three stick relays F^E, F^W, and F^C, and these relays are in turn controlled by three selectors X^E, X^W, 65 and X^C. These selectors are controlled from a remote point such as a despatcher's office. Each selector comprises a normally open contact 6 which momentarily becomes closed when the selector receives the code impulse 70 combination to which it is designed to respond. A fourth selector X^R is provided for a purpose which will appear hereinafter.

Each arm of each signal is provided with a control relay designated by the reference 75 character H with a suitable exponent and a suitable subscript. For example, the main arm 3^M of signal S^E is provided with a control or home relay H^M_E, and the signal arm is controlled by a contact 32 of this relay through 80 a circuit which will be obvious from the drawing.

I will assume that switch S is in the normal position, and that the despatcher desires to permit an eastbound train to pass through the 85 section A—D. To do this, he operates selector X^E. When contact 6 of this selector becomes closed, it closes a pick-up circuit for relay F^E, which circuit is from terminal B of a suitable source of current, through wire 5, 90 contact 6 of selector X^E, wire 7, and the winding of relay F^E to terminal O of the same source of current. As soon as relay F^E becomes closed, a stick circuit for this relay is closed, which circuit passes from terminal B, 95 through resistance 8, back contact 9 of relay F^W, front contact 10 of relay F^E and the winding of relay F^E to terminal O. It follows that relay F^E will remain closed if and only if relay F^W is de-energized. If the track section 100

A—D is unoccupied, so that track relay T is energized, home relay H^M_E will become closed, its circuit being from terminal B, through contact 17 of track relay T, front contact 18 of relay F^E , front contact 19 of indication relay K, polar contact 20 of relay K in the normal position, and winding of relay H^M_E to terminal O. It will be noted that this circuit cannot be closed if the track section 5 A—D is occupied. When relay H^M_E becomes closed, it will close at contact 32 the circuit for the main arm 3^M of signal S^E . As soon as the eastbound train enters section A—D it will open track relay T, thereby de-energizing 10 relay H^M_E , with the result that signal arm 3^M will return to the stop position. Relay F^E will, however, remain energized.

If switch S be in the reverse position when selector X^E is operated, relay H^A_E will become energized, its circuit being from terminal B, through contact 17 of track relay T, contact 18 of relay F^E , contact 19 of relay K, contact 20 of relay K in the reverse position, and the winding of relay H^A_E to terminal O. The circuit for the auxiliary arm 3^A 15 of signal S^E will then be closed at contact 33 of relay H^A_E , so that this arm will move to the clear position.

I will now assume that the despatcher desires to permit a westbound train to pass through section A—D. To do this, he operates selector X^W , thereby closing the pick-up circuit for relay F^W ; this circuit is from terminal B, through wire 5, contact 6 of selector X^W , wire 11, and the winding of relay F^W to terminal O. As soon as relay F^W becomes energized, a stick circuit for this relay is closed, which circuit passes from terminal B through resistance 8, back contact 12 of relay F^E , front contact 13 of relay F^W , and the winding of relay F^W to terminal O. If switch S be in the normal position relay H^M_W will become energized, its circuit being from terminal B through contact 21 of track relay T, contact 22 of relay F^W , neutral contact 23 of relay K, polar contact 24 of relay K in the normal position, and the winding of relay H^M_W to terminal O. The circuit for arm 3^M of signal S^W will then become closed at contact 35 of relay H^M_W . If switch S be in the reverse position, relay H^A_W will become energized because contact 24 of relay K will be in the reverse position.

I will now assume that section A—D is occupied by an eastbound train, that relay F^E is still energized, and that the despatcher desires to permit a second eastbound train to enter this section. To do this, he operates selector X^C , thereby closing the pick-up circuit for relay F^C , which circuit is from terminal B through wire 5, contact 6 of selector X^C , wire 14 and the winding of relay F^C to terminal O. Relay F^C then remains energized by virtue of a stick circuit which passes 60 from terminal B, through resistance 8, front

contact 15 of relay F^C , and the winding of this relay to terminal O. Relay F^E being also energized, relay H^C will become energized, its circuit being from terminal B, through contact 25 of relay F^C , contact 26 of relay F^E , back contact 27 of relay H^A_E , back contact 28 of relay H^M_E , and the winding of relay H^C to terminal O. It will be noted that this circuit cannot be closed unless both relays H^A_E and H^M_E are de-energized. The circuit 70 for the calling-on arm 3^C of signal S^E will now be closed at contact 34 of relay H^C .

If section A—D be occupied by a westbound train and the despatcher desires to permit a second westbound train to enter the section, he will actuate selector X^C , as before, to energize relay F^C , with the result that this relay and relay F^W will both be energized. Relay H^C_W will then become energized by virtue of a circuit which passes from terminal B, through contact 25 of relay F^C , contact 29 of relay F^W , back contact 30 of relay H^A_W , back contact 31 of relay H^M_W , and the winding of relay H^C_W to terminal O. The circuit for calling-on arm 3^C of signal S^W will then become closed at contact 37 of relay H^C_W .

When selector X^R is operated to close its contact 6, this contact will momentarily close a shunt around the windings of stick relays F^E , F^W , and F^C , so that whatever one or whatever two of these relays are then energized will become de-energized.

Although I have herein shown and described only one form of signaling system embodying my invention, it is understood that various changes and modifications may be made therein within the scope of the appended claims without departing from the spirit and scope of my invention.

Having thus described my invention, what I claim is:

1. In combination, a section of railway track, a track circuit including a track relay for said section, an eastbound main signal and a westbound main signal for said section, an eastbound calling-on signal and a westbound calling-on signal for said section, an eastbound stick relay and a westbound stick relay, an eastbound home relay for said eastbound main signal, a westbound home relay for said westbound main signal, a calling-on stick relay, an eastbound calling-on relay for said eastbound calling-on signal, a westbound calling-on relay for said westbound calling-on signal, a pick-up circuit for said eastbound stick relay including a normally open contact controlled from a remote point, a pick-up circuit for said westbound stick relay including a normally open contact controlled from said remote point, a stick circuit for each of said eastbound and westbound stick relays each including a back contact of the other relay, a circuit for said eastbound home relay including a front con-

tact of said eastbound stick relay and a front contact of said track relay, a circuit for said westbound home relay including a front contact of said westbound stick relay and a front contact of said track relay, a pick-up circuit for said calling-on stick relay including a normally open contact controlled from said remote point, a stick circuit for said calling-on stick relay, a circuit for said eastbound calling-on relay including a front contact of said calling-on stick relay as well as a front contact of said eastbound stick relay and a back contact of said eastbound home relay, a circuit for said westbound relay including a front contact of said calling-on stick relay as well as a front contact of said westbound stick relay and a back contact of said westbound home relay, and means controlled from said remote point for de-energizing all of said stick relays.

2. In combination, a section of railway track, a track circuit including a track relay for said section, an eastbound main signal and a westbound main signal for said section, an eastbound calling-on signal and a westbound calling-on signal for said section, an eastbound stick relay and a westbound stick relay, an eastbound home relay for said eastbound main signal, a westbound home relay for said westbound main signal, a calling-on stick relay, an eastbound calling-on relay for said eastbound calling-on signal, a westbound calling-on relay for said westbound calling-on signal, means including selectors for energizing said stick relays, means for energizing the eastbound or the westbound home relay provided the associated stick relay and said track relay are energized, and means operating when said calling-on stick relay is energized to energize the eastbound or the westbound calling-on relay according as the eastbound or the westbound stick relay is energized and provided the associated home relay is de-energized.

3. In combination, a section of railway track, a track circuit including a track relay for said section, an eastbound main signal and a westbound main signal for said section, an eastbound calling-on signal and a westbound calling-on signal for said section, an eastbound relay, a westbound relay, and a calling-on relay, means including selectors for energizing said relays, means for clearing said eastbound or said westbound main signal according as said eastbound or said westbound relay is energized provided said track relay is also energized, and means operating when said calling-on relay is energized to clear either the eastbound or the westbound calling-on signal according as the eastbound or the westbound relay is energized and provided said track relay is de-energized.

4. In combination, a section of railway track containing a switch, a track circuit

including a track relay for said section, a main signal and an auxiliary signal as well as a calling-on signal governing eastbound traffic through said switch, a main signal and an auxiliary signal as well as a calling-on signal governing westbound traffic through said switch, an eastbound relay, a westbound relay and a calling-on relay, means including selectors for energizing said relays, means operating when said eastbound relay is energized to clear the main or the auxiliary eastbound signal according as said switch is in the normal or the reverse position and provided said track relay is energized, means operating when said westbound relay is energized to clear the main or the auxiliary westbound signal according as said switch is in the normal or the reverse position and provided said track relay is energized, and means operating when said calling-on relay is energized to clear said eastbound or said westbound calling-on signal according as said eastbound or said westbound relay is energized and provided said track relay is de-energized.

In testimony whereof I affix my signature.
PAUL P. STOKER.
